(57) **CLAIM**

The ornamental design for a battery charging station, as shown and described.

DESCRIPTION

FIG. 1 is a perspective view of a battery charging station, showing a recess for receiving batteries to charge the batteries, a lid covering the recess, and interfaces for connecting to external components to charge the batteries of the external components in broken lines;

FIG. 2 is a front view of the battery charging station, showing the interfaces and a switch for choosing between different battery types in broken lines;

FIG. 3 is a rear view of the battery charging station;

FIG. 4 is a left side view of the battery charging station;

FIG. 5 is a right side view of the battery charging station, showing an interface for receiving an external power cord in broken lines;

FIG. 6 is a top view of the battery charging station, showing the recess, indicator lights, and a screen in broken lines;

FIG. 7 is a bottom view of the battery charging station; and,

FIG. 8 is a perspective view of the battery charging station with the lid in an open position.

The broken lines shown in the drawings are included for the purpose of illustrating environmental structure and form no part of the claimed design.

1 Claim, 6 Drawing Sheets
